UNITED STATES PATENT OFFICE

2,600,961

COIN STORING AND DISPENSING DEVICE

Harry C. Biehl, Berwick, Pa.

Application December 13, 1948, Serial No. 64,985

2 Claims. (Cl. 133—5)

1

This invention relates to coin storing and dispensing devices and has special reference to devices of this character having means for storing coins of different values and for selectively dispensing such coins.

One important object of this invention is to provide a novel compact device of this character capable of being carried in a woman's purse or man's pocket.

Another object of the invention is to provide a novel device of this class wherein coins may be deposited and securely held without the necessity of it being opened in some manner, such as by a hinged, sliding or removable door, in order to gain access to the coin storage compartments.

A further object of the invention is to provide a novel construction of such a device wherein the main portion of the device holds the movable parts and coins and is made from a single cast or molded body, this body being closed by two simple cover plates.

A still further object of the invention is to provide, in such a device, a novel and simple form of dispensing mechanism wherein a single spring is used to effect dispensing of coins of different values.

Yet another object of the invention is to provide a novel arrangement of filling means operable upon inversion of the device and having openings for the reception of coins provided with adjacent indicia readable with the device inverted and indicating the values of the coins to be inserted in the different slots.

With the above and other objects in view, as will be presently apparent, the invention consists in general of certain novel details of construction and combinations of parts hereinafter fully described, illustrated in the accompanying drawings and particularly claimed.

In the accompanying drawings like characters of reference indicate like parts in the several views, and:

Figure 1 is a perspective view of the invention in coin dispensing position.

Figure 2 is a top plan view of the invention with the top cover plate removed.

Figure 3 is a bottom plan view of the invention with the bottom cover plate removed.

Figure 4 is an enlarged section on the line 4—4 of Fig. 2, and

Figure 5 is a section on the line 5—5 as shown in Figs. 2 and 4.

The main parts of the form of the device as here shown consist of a flat shallow casing body 10, top cover plate 11 and bottom cover plate 12. As here shown these parts are of such shape as

to form a generally rectangular oblong structure in plan but it is to be understood that the exterior of the device may have rounded edges and corners and may be plain or ornamental as desired.

Considering the device in the position shown in Fig. 1, the body 10 is provided at each corner with a circular transverse coin receiving cell 13 of proper diameter to receive the desired value of coin C to be stored therein. For the present example, the four cells 13 are of proper sizes to receive coins of the respective values of one, five, ten and twenty-five cents but other arrangement of cell sizes may be made if desired. These cells 13 extend transversely vertically through the body 10 from the top thereto to the upper surface of shallow recesses 14 extending longitudinally of the bottom of the body in aligned pairs. The vertical depth of these recesses corresponds to the thickness of the coins to be passed therethrough. The tops of the cells 13 are closed by the cover plate 11 held on the body by screws 15 and the recesses 14 are similarly closed by the cover plate 12, the ends of the recesses at the ends 16 of the device forming coin receiving and delivery slots.

It will be observed that the cells 13 are arranged in pairs adjacent each side of the body 10 with the axes of each pair equidistant from a respective side of the body 10. Axially aligned between each pair of cells is a tubular channel 17 opening into the recesses 14 of the pair through a slot 18. In each of the recesses 14 is slideably fitted a disc 19 having at its outer end an arcuate notch 20 of proper radius to fit the coins carried in the adjacent cell 13. Opposite the notch 20 diametrically at their inner ends each slide has a perpendicular lug 21 provided with an enlarged circular upper end 22 fitting slideably in the channel 17. From the upper ends 22 of each pair of lugs 21 project aligned inwardly extending horizontal pins 23, the pins on the two upper ends projecting toward each other. The ends of a coiled compression spring 24 fit over the pins 23 of each pair and this spring urges the discs 19 of each pair simultaneously outward towards the ends 16 of the body 10. In their outward positions each disc 19 partially closes the lower end of a cell 13 thus supporting the coins C in that cell. Extending up from each channel 17 is a pair of transverse slots 25 opening into said channels and towards the ends of the body in vertical bores 26. Across the slots 25 extend pivot screws 27 and on each of these screws is pivoted a lever 28 having a downwardly extending finger 29 against which the enlarged end 22 is urged by the

spring 24. The upper edge 30 of each lever 28 is flat beveled and inclined inwardly and on this edge is engaged the bifurcated enlarged end 31 of an operating pin 32 which passes through an opening 33 in the cover 11. The part of the bifurcation engaging the edge 30 is rounded to obtain a camming effect on the inclined upper edge of the lever and the shoulders formed by the enlargement and arms of the bifurcation limit the movement of the pin 32 upwardly by engagement with the cover 11 on each side around opening 33. This limits upward movement of the lever 28 which through the action of the finger 19 limits movement of the disc 19 by the spring 24.

The ends 16 of the body are provided with vertical slots 34 opening into the cells 13 so that the number of coins in these cells may be observed. The cover plate 11 is provided with indicia 35 adjacent the pins 32 to indicate the unit values of coins controlled by each pin and the delivery and loading slots 14 in the ends 16 have like indicia 36 adjacent the respective slots, these latter indicia being inverted. The indicia 35 and 36 may be impressed or engraved in the surface of the device, painted thereon in contrasting color to the body or otherwise shown. In order to avoid unnecessary weight the body 10 may have recesses or passages 37 formed therein with voids between slots 25 and pores 26, and the side walls of the body casing.

In using the device it is first loaded by inverting it from the position shown in Fig. 1. Observing the indicia (now right side up) the user pushes down and holds down the pin 32 closest to the entry slot for the unit value of the coin to be deposited. With the pin 32 in depressed position the lever 28 is rocked and the slide 19 retracted as at the right of Fig. 4. The proper coin or coins are then inserted at recess 14 whereupon they will drop in the cell and accumulate against the plate 11. Other cells may be supplied with coins in like manner. Upon the user having inserted all the coins he desires or when the capacity of the device has been reached, the device is turned to the erect position of Fig. 1, the pins 33 being left in protracted position. The slides will now be in outward positions and the coins in the cells will rest with the bottom coin of each of the usual piles on top of the respective slide 19. For dispensing a coin the pin 33 indicated by the adjacent index for the desired coin is depressed to bias lever 28 downwardly and inwardly. This moves the slide 19 inwardly as at the right of Fig. 4 and the pile of coins drops so that the bottom coin of the pile rests on the plate 12. The pin 33 is now released and the slide will move outwardly under influence of the spring 24 and eject one coin, the remainder of the pile being supported by the slide. By repeating this operation for the same or other coin values the amount desired may be readily supplied.

What is claimed is:

1. In a coin storing and dispensing device, a casing including a body having recesses in its under side terminating in coin delivery slots, said body having coin receiving cells extending from the top of the body to said recesses, a disc in each of said recesses slideably movable between a protracted position at least partially closing a respective cell bottom and a retracted position leaving said cell bottom open, said discs each having an upstanding lug, a rockable lever for each disc pivoted in the body and having a downwardly extending finger freely engaging

the disc lug to retract the same upon downward biasing of said lever, depressible pins slidably engaging the levers to bias the same, said discs being arranged in pairs with their lugs having confronting and aligned coil spring supporting pins, a single coiled spring engaged between each pair of said upstanding lugs and seated on said spring supporting pins, a top cover plate secured to said body and closing the upper ends of said cells, said top cover plate having openings where-through said pins protrude, and a bottom cover plate secured to said body and closing said recesses.

2. In a coin storing and dispensing device, a flat shallow rectangular casing including a body having longitudinally aligned pairs of recesses in its underside terminating in outer coin delivery slots extending through opposed ends of the body, said body having pairs of transverse coin receiving cells extending from the top of the body of said recesses, horizontal longitudinal bores between the cells and recesses and establishing communication therebetween, there being transverse slots opening into said bores, a disc in each of said recesses slideably movable in opposite directions between a protracted position at least partially closing a respective cell bottom and a retracted position leaving said cell bottom open, said discs each having an upstanding lug at its inner end with a circular enlargement movable in a bore, a rockable lever pivoted horizontally in each slot and having an inwardly inclined top edge and a downwardly extending finger engaging at the outer side of a lug enlargement, said lug enlargements each having an inwardly projecting pin, a single coiled compression spring in each longitudinal bore engaged at its ends on said pins between aligned opposed pair of discs and lugs to normally hold the same outward, a top cover plate secured to the body and closing the upper ends of the cells, said top cover plate having openings over the slots, depressible pins having enlarged bifurcated lower ends and beveled and rounded at the bifurcation to straddle and slidably engage said inclined top edge of a lever and outward shoulders to engage under the top cover plate to limit projection of the pin, said rounded portion and inclined edge producing a camming action to rock the lever upon depression of a pin to move the finger inwardly against a lug to retract a disc and uncover a cell bottom for dropping of a coin into a recess and discharge therefrom under compression of a spring upon releasing the pin in each pair, and a bottom cover plate secured to said body and closing said recesses.
